UNITED STATES PATENT OFFICE

113,244

DESIGN FOR A FLAG

Ambrose J. Tomlinson, Cleveland, Tenn., assignor to The Church of God, Cleveland, Tenn., through its trustees

Application November 10, 1938, Serial No. 81,025

Term of patent 7 years

To all whom it may concern:

Be it known that I, Ambrose J. Tomlinson, a citizen of the United States, residing at Cleveland, in the county of Bradley and State of Tennessee, have invented a new, original, and ornamental Design for a Flag, of which the following is a specification, reference being had to the accompanying drawing, forming part thereof.

The figure is an elevational view of a flag, showing my new design.

I claim:

The ornamental design for a flag, as shown.

AMBROSE J. TOMLINSON.

DESIGN No 113,244

Renewed and extended by Act of Congress, approved July 11, 1946, for a period of fourteen years from date of Act. 60, Stat.
1254.
